UNITED STATES PATENT OFFICE.

NELSON D. RIEMENSCHNEIDER, OF STATE CENTER, IOWA.

TANK-HEATER.

1,241,555.

Specification of Letters Patent.

Patented Oct. 2, 1917.

Application filed November 17, 1916. Serial No. 131,838.

To all whom it may concern:

Be it known that I, NELSON D. RIEMENSCHNEIDER, a citizen of the United States, residing at State Center, in the county of Marshall and State of Iowa, have invented certain new and useful Improvements in Tank-Heaters, of which the following is a specification.

This invention relates to improvements in tank heaters and one of the objects of the same is to provide an improved device of this character which will be simple, durable and cheap in construction and effective and efficient in operation, and one in which liquid fuel such as kerosene may be employed as a heating medium.

To the attainment of these ends and the accomplishment of other new and useful objects as will appear, the invention consists in the features of novelty in substantially the construction, combination and arrangement of the several parts hereinafter more fully described and claimed and shown in the accompanying drawing, illustrating the invention and in which—

Figure 1 is a vertical longitudinal sectional view of an improved device of this character constructed in accordance with the principles of this invention and showing the same applied to a tank.

Fig. 2 is a detail horizontal sectional view taken on line 2—2, Fig. 1.

Fig. 3 is a view similar to Fig. 1 of a portion of the heater, showing a modified form thereof.

Referring more particularly to the drawing, the numeral 10 designates a heating chamber, which may be of any desired size and configuration, and constructed of any suitable material.

The bottom of the chamber is open and a closure 11 is provided therefor which rests against the open edge of the bottom of the chamber and a gasket 12 of any suitable material may be interposed between the closure and the edge of the chamber for securing a fluid tight joint. The closure is held in position in any suitable manner such as by means of fastening devices 13, which permit the closure to be readily removed when desired. Suitable supports 14 may also be provided, if desired, to hold the chamber above the bottom of the tank 15, although these supports are not necessary.

Arranged within the chamber 10 is a lamp 16 preferably adapted for the use of kero-

sene and the lamp is provided with a wick adjusting stem 17 to which is secured a gear 18.

Projecting through the upper end of the chamber is a pipe 19, which extends for some distance above the chamber and terminates within the chamber. A shaft 20 passes through this pipe 19 and one end of the shaft is journaled in a suitable bearing 21, while the other extremity 22 of the shaft projects beyond the extremity of the pipe 19 and a detachable handle 23 is connected to the extremity of the shaft.

A gear 24 is also connected with the shaft 20 within the chamber 10 and this gear meshes with the gear 18 so that when the shaft 20 is rotated by the handle 23, the gear 18 and the wick adjusting stem 17 will be actuated, to raise and lower the wick.

Air is supplied to the interior of the chamber 10 to support combustion by means of a suitable air supply pipe 25, which projects into the tank and preferably terminates at a point below the flame of the lamp.

The other extremity 26 of the pipe 25 is located some distance beyond the chamber and above the water level in the tank.

Another pipe 27, similar to the pipe 25, projects into the chamber 10, the extremity 28 of the pipe terminating preferably at a point above the flame, so as to receive the gases and products of combustion from the chamber, and which gases will be discharged through the extremity 29 of the pipe 27, and which extremity 29 is also located above the water level of the tank. The heater is secured in position in the tank and held submerged in any desired or suitable manner, such as by means of anchor rods 30, which engage suitable anchors 31 in the bottom of the tank and also ears or projections 32 on the chamber 10. Suitable thumb screws 33 may be provided on the anchor rods 30 to permit ready removal of the heater.

Oil is supplied to the lamp preferably through a pipe 34, which extends into the chamber 10 and has communication with the oil reservoir of the lamp. This pipe 34 terminates above the water level in the tank and is closed by a cap 35, so that when it is desired to fill the lamp, the cap 35 may be removed and the oil passed through the pipe 34 to the reservoir. A float 36 may be provided which has an indicator 37 connected thereto, and this indicator extends through

the pipe 34 so that the operator may readily ascertain the quantity of oil in the lamp.

With this improved construction it will be manifest that after the lamp is once lighted and the heater secured in position in the tank, the lamp can not only be controlled from the outside of the tank without removing the heater, but the lamp may also be filled while the tank is submerged and the operator can readily ascertain the amount of oil in the lamp without removing the heater.

The air being supplied through the pipe 25 to the chamber 10 supports the combustion of the lamp and the gases and smoke will pass out of the pipe 27.

In the form of the invention shown in Fig. 3, a coil 38 is provided within the chamber 10. This coil has an inlet 39 opening 20 through the wall of the chamber and an outlet 40 opening through the wall of the chamber and the coil being in communication with the tank, the water will flow into the coil which is arranged around the wall 25 of the chamber inside thereof, and pass out of the outlet 40. This will not only assist in heating the water but will induce a circulation of the water in the tank.

While the preferred forms of the invention have been herein shown and described, it is to be understood that many changes may be made in the details of construction, and in the combination and arrangement of the several parts without departing from 35 the spirit of this invention.

What is claimed as new is:

1. A tank heater embodying a heating chamber, a burner within the chamber, a feed pipe for the burner extending through 40 the top of the chamber, an upright air inlet pipe extending into the chamber through the top thereof and terminating adjacent the burner, an upright air outlet pipe also extending through the top of the chamber 45 and terminating adjacent the burner, the ends of the air pipes within the chamber terminating in different horizontal planes, a burner controlling shaft extending through the top of the chamber, and an upright casing 50 for the shaft, said casing extending through the top of the chamber.

2. A tank heater embodying a heating chamber, a burner within the chamber, a feed pipe for the burner extending through 55 the top of the chamber, an upright air inlet pipe extending into the chamber through the top thereof and terminating adjacent the burner, an upright air outlet pipe also extending through the top of the chamber

and terminating adjacent the burner, the ends of the air pipes within the chamber terminating in different horizontal planes, a burner controlling shaft extending through the top of the chamber, an upright casing for the shaft, said casing extending through 65 the top of the chamber, said chamber having an open bottom, a closure for the bottom, and fastening means for securing the closure.

3. A tank heater embodying a heating 70 chamber, a burner within the chamber, a feed pipe for the burner extending through the top of the chamber, an upright air inlet pipe extending into the chamber through the top thereof and terminating adjacent 75 the burner, an upright air outlet pipe also extending through the top of the chamber and terminating adjacent the burner, the ends of the air pipes within the chamber terminating in different horizontal planes, 80 a burner controlling shaft extending through the top of the chamber, an upright casing for the shaft, said casing extending through the top of the chamber, a tank adapted to receive the heater, and anchor rods connected with the tank, said rods having detachable connection with the heater for removably securing the heater in position.

4. A tank heater embodying a heating chamber, a burner within the chamber, a feed pipe for the burner extending through 90 the top of the chamber, an upright air inlet pipe extending into the chamber through the top thereof and terminating adjacent the burner, an upright air outlet pipe also 95 extending through the top of the chamber and terminating adjacent the burner, the ends of the air pipes within the chamber terminating in different horizontal planes, a burner controlling shaft extending through 100 the top of the chamber, an upright casing for the shaft, said casing extending through the top of the chamber, a tank adapted to receive the heater, anchor rods connected with the tank, said rods having detachable 105 connection with the heater for removably securing the heater in position, and a coil within the chamber, both ends of the coil passing through the wall of the chamber and having communication with the interior 110 of the tank.

In witness whereof, I hereunto subscribe my name to this specification in the presence of two witnesses.

NELSON D. RIEMENSCHNEIDER.
